UNITED STATES PATENT OFFICE.

THADDIOUS V. ELLIOTT, OF NEW YORK, N. Y., ASSIGNOR TO MARIEA ELLIOTT,
OF FLATBUSH, NEW YORK.

CLEANING DEVICE FOR FEED-WATER HEATERS.

No. 903,132.

Specification of Letters Patent.

Patented Nov. 3, 1908.

Application filed May 1, 1905, Serial No. 258,271. Renewed March 13, 1908. Serial No. 420,803.

To all whom it may concern:

Be it known that I, THADDIOUS V. ELLIOTT, a citizen of the United States, and a resident of the city of New York, Flatbush, borough 5 of Brooklyn, in the county of Kings and State of New York, have invented a new and Improved Cleaning Device for Feed-Water Heaters, of which the following is a full, clear, and exact description.

10 The object of the invention is to provide a new and improved cleaning device, more especially designed for effectively cleaning feed water heaters whenever desired, without requiring shutting off the feed water 15 from the boiler.

The invention consists of novel features and parts and combinations of the same, as will be more fully described hereinafter and then pointed out in the claims.

20 A practical embodiment of the invention is represented in the accompanying drawings forming a part of this specification, in which similar characters of reference indicate corresponding parts in all the views.

25 Figure 1 is a side elevation of the improvement as applied, the furnace being shown in longitudinal section, on the line 1—1 of Fig. 2; Fig. 2 is a front elevation of the same, partly in section, on the line 2—2 of Fig. 1;

30 Fig. 3 is an enlarged sectional side elevation of the improvement, on the line 3—3 of Fig. 4; Fig. 4 is a transverse section of the same, on the line 4—4 of Fig. 3; and Fig. 5 is a sectional plan view of the same, on the line 35 5—5 of Fig. 3.

The feed water heater, as shown in the drawings, is arranged in the heating chamber A of the boiler B, set in the usual brick-work C of the furnace, and the said feed 40 water heater is preferably made in two sections, one on each side of the heating chamber A, the sections extending longitudinally in the furnace so as not to interfere with the water-box and other parts of the furnace.

45 Each section of the feed water heater is formed of horizontally disposed tubular members D, D' and D², located one above the other and preferably rectangular in cross section, as indicated in Figs. 2 and 4. The 50 sections D and D' are connected with each other by vertical pipes D³ and similar pipes D⁴ connect the sections D' and D² with each other, and the forward end of the section D' is connected with a water supply pipe E extending through the front wall of the fur-

nace to the outside thereof to connect with a suitable water supply.

The several sections D, D' and D² are connected by pipes F, F' and F² with a pipe F³ leading into the water compartment of the 60 boiler B, so as to discharge the heated feed water into the said boiler from the said sections D, D' and D².

In order to subject the feed water in the feed water heater to the same pressure as 65 that of the steam in the boiler, the several sections D, D' and D² are connected by pipes G, G' and G² with a pipe G³ leading into the top or steam compartment of the boiler B. The inner end of the section D' is connected 70 by a pipe H, having a check valve H', with a blow-off pipe H² leading from the bottom of the boiler B to a discharge pipe H³, having a valve H⁴ which, when opened, allows the discharge of the water and steam contained in the boiler B. The forward end of the lower section D² of the feed water heater forms the mud drum and is provided with a blow-off pipe I having a valve I'.

In order to allow of periodically cleaning 80 the interior surfaces of the sections D, D' and the pipes D³, D⁴, without interrupting the proper working of the feed water heater, the following cleaning device is provided:

In the middle section D' of the feed water 85 heater are arranged longitudinally extending bars J and J', spaced a suitable distance apart and extending at their forward ends through a portion of the supply pipe E and through a suitable stuffing box K to the outside of the furnace, the outer ends of the said bars J and J' being connected with hand levers L and L', fulcrumed on links L², pivoted on brackets L³ attached to the pipe E. By the operator taking hold with both hands 90 of the hand levers L and L' and swinging the same in opposite directions, a longitudinal sliding motion is given to the bars J and J' in opposite directions. The bars J and J', within the section D', are provided with 95 spaced scrapers J² and J³, in engagement with the inner surface of the section D', and the said scrapers are placed suitable distances apart so that when the bars J and J' are moved longitudinally in opposite directions, 100 the said scrapers scrape the entire inner surface of the section D', the sliding movement given to each bar being somewhat in excess of one-half the distance between adjacent sides of the scrapers J² and J³. The scraper 110

bars J and J' are provided at their inner surfaces with racks J⁴ and J⁵ arranged in the bars and in mesh with opposite sides of pinions N, having cross-shaped hubs N', extending at their upper ends into the lower part of the corresponding connecting tube D³, and the lower end of the said hub N' extends into the connecting tube D⁴, between the sections D' and D². On both ends of each hub 10 N' are secured scrapers O and O', of which the scraper O extends to the top of the tube D³ and the scraper O' extends to the lower end of the tube D⁴. Each of the scrapers O and O' is in the shape of a flat bar in contact at its side edges with the inner surface of the corresponding tube D³ or D⁴, and when the bars J and J' receive a sliding motion in opposite directions, as previously explained, then the corresponding pairs of 15 racks J⁴, J⁵ rotate the pinions N, so that a rotary motion is given to the scrapers O and O', to turn the same completely around in the tubes D³ and D⁴ and scrape the inner surfaces thereof.

20 25 A scraper bar P extends lengthwise in the upper section D of the feed water heater and on this scraper bar P are secured scrapers P', similar to the scrapers J³ and in contact with the inner surface of the section D. The 30 scraper bar P extends its forward end through a pipe D⁵ passing through the front wall of the brickwork C, and the outer end of the said scraper bar P also passes through a stuffing box K' held on the terminal of the 35 pipe D⁵. A lever P² is pivotally connected with the outer end of the scraper bar P, and this lever P² is fulcrumed on a link P³, pivoted to a bracket P⁴ attached to the pipe D⁵. By the operator imparting a swinging 40 motion to this lever P², the bar P is moved lengthwise in the section D and consequently its scrapers P' scrape the inner surface of the said section D. The material scraped off the inner surface of the section D is carried by the scrapers P' to the tubes D³, through which the said material can fall down and through the section D' and tube D⁴, to finally reach the mud-drum section D², and in a like manner the material scraped 45 off in the tubes D³ flows down to the mud-drum, and likewise the material scraped in the section D' and the tubes D⁴ finally passes into the mud-drum section D². The latter is blown off from time to time by the operator 50 opening the valve I', to discharge the sediment or scraped-off material by way of the pipe I to a suitable place of discharge.

55 From the foregoing it will be seen that the cleaning device forms a permanent fixture 60 of the feed water heater and can be actuated from time to time by the operator, to scrape off any material that may have collected on the inner surfaces of the sections and pipes of the feed water heater, and the scraped-off 65 material can be finally removed from the

mud-drum section D² into which it passes by opening the valve I' from time to time, as previously mentioned.

The sections D and D' and pipes D³, D⁴ are made sufficiently large to readily accommodate the members of the cleaning device, so as to provide sufficient space for the amount of feed water required for properly feeding the boiler B.

Having thus described my invention, I 75 claim as new and desire to secure by Letters Patent:

1. The combination with a feed water heater comprising communicating horizontal and vertical members of a cleaning device 80 therefor, comprising longitudinal bars spaced apart and extending within a horizontal member of the feed water heater, scrapers attached to the bars, a pair of hand levers connected with the outer ends of the bars to move the same lengthwise in opposite directions, racks attached to the bars and arranged in pairs, shafts in the vertical members of the heater, and extending into the horizontal member, pinions secured to the 85 shafts and in mesh on opposite sides with the racks, and longitudinally disposed scrapers on the shafts within the vertical members.

2. The combination with a feed water heater, comprising communicating horizontal and vertical members, of a cleaning device 95 therefor, comprising longitudinal bars spaced apart and extending within a horizontal member of the feed water heater, scrapers attached to the bars, a pair of hand levers connected with the outer ends of the bars to move the same lengthwise in opposite directions, shafts in the vertical members extending into the horizontal member, longitudinally disposed scrapers on the shafts, and 100 means whereby the movement of the bars may rotate the shafts.

3. The combination with a feed water heater comprising vertical and longitudinal members of a cleaning device permanently 110 arranged within the members, comprising reciprocating scrapers in the horizontal members, rotary scrapers in the vertical members, means whereby to reciprocate the first named scrapers, and means whereby the reciprocation 115 of the said scrapers may rotate the scrapers in the vertical members.

4. The combination with a feed water heater, comprising communicating vertical and horizontal members, of reciprocating 120 scrapers in the horizontal members, rotary scrapers in the vertical members, and means for simultaneously actuating all the scrapers.

In testimony whereof I have signed my name to this specification in the presence of 125 two subscribing witnesses.
